Philip D. Reed

UNITED STATES PATENT OFFICE.

JOHN M. VAN HEUSEN, OF BOSTON, MASSACHUSETTS.

NECKBAND.

Application filed October 4, 1922. Serial No. 592,335.

To all whom it may concern:

Be it known that I, JOHN M. VAN HEUSEN, a citizen of the United States, and a resident of Boston, in the county of Suffolk and State of Massachusetts, have invented certain new and useful Improvements in Neckbands, of which the following is a specification.

The present invention relates to neckbands for shirts and methods of attaching the same, and more particularly to neckbands made of semi-stiff fabric such, for example as multiple ply interwoven fabric.

Heretofore neckbands have been made of a plurality of layers of fabric folded or cut to the desired shape and stitched together. The pocket at the back buttonhole portion of these neckbands necessitates additional cutting and piecing and also requires additional sewing machine operations. Neckbands of this type are costly of manufacture because of the great amount of labor and time required in cutting, shaping, piecing and stitching together the several pieces of fabric of which they are composed. Furthermore, neckbands of this type have practically no body or stiffness and consequently require the use of starch in the laundering process.

In my Patent No. 1,277,788 granted September 3, 1918, I describe and illustrate a neckband made of a fabric having sufficient weight and body to obviate the necessity of starch or other stiffening means. I describe means whereby the neckband may be woven of any shape or size desired, and I also describe a neckband provided with means whereby it can be attached to the shirt by a single sewing machine operation.

According to one embodiment of my invention patented in my said Patent No. 1,277,788, I provide during the weaving operation a pocket in the back buttonhole portion of the neckband. The present invention relates in part to a neckband having an improved back buttonhole portion and to methods of attaching the said neckband to a shirt or similar article.

The neckband of my present invention is made of semi-stiff fabric, such, for example, as multiple ply interwoven fabric. By the term semi-stiff I do not mean to define any particular degree of stiffness, but I use it in a broad sense, as including all fabrics which in an unstarched condition possess

greater inherent stiffness than the ordinary unstarched fabric of which neckbands are commonly made, such, for example, as handkerchief cloth or cambrics, etc.

According to one embodiment of my invention I weave a strip of two ply interwoven fabric of the shape and size desired for a neckband. At the point corresponding to the back buttonhole portion of the neckband, I weave a pocket by separating the plies of the fabric, said pocket being closed at its top and side edges and open at the bottom edge. I also weave along the bottom edge of the neckband fabric a divided edge formed by the separate extensions of the two ply fabric. In attaching the neckband to the shirt I secure the shirt fabric between the divided edge of the neckband. At the backbutton hole portion I secure the shirt between one of the edges of the divided edge and the edge of an additional rectangular strip of fabric which is inserted into the buttonhole pocket and secured. In this way I provide adequate means for securing the shirt to the neckband, and, at the back buttonhole portion, I leave one of the plies which form the pocket unattached to the shirt and open at the lower edge so the collar button may be inserted therein.

My invention will be more particularly described in connection with the accompanying drawings illustrative of certain embodiments thereof, in which—

Fig. 1 is a perspective view of the neckband attached to the shirt.

Fig. 2 is a plan view of the neckband showing the back buttonhole portion.

Fig. 3 is a plan view showing a portion of the neckband of Fig. 2 and having the upper layer of fabric cut along the center of the pocket and folded back.

Fig. 4 is an enlarged and diagrammatical sectional view taken on the line 4—4 of Fig. 3.

Fig. 5 is an enlarged and diagrammatical sectional view taken on the line 5—5 of Fig. 2.

Fig. 6 is an enlarged and diagrammatical sectional view taken on the line 6—6 of Fig. 2.

Fig. 7 is a perspective view showing the first step in the preferred method of attachment.

Fig. 8 is a perspective view showing the

central portion of the neckband attached to the shirt.

In the drawings Fig. 1 shows the neckband of the present invention as it would appear when attached to a shirt. The back buttonhole pocket 1 is open at the lower edge 2 thereof to permit the insertion of a collar button in the buttonhole 3.

The pocket 1 may be produced in any desired manner. In the two ply interwoven fabric of which my preferred neckband is constructed, I produce the back buttonhole pocket by so operating the loom (while weaving the said back buttonhole portion) as to weave the two plies of the fabric separate and unconnected; that is, the interweaving operation, which normally consists in passing a set of warp threads (known as interweave or binder threads) through both plies of the fabric and binding them together, is suspended. In the preferred embodiment the pocket does not extend the entire width of the neckband so as to produce a tube, but stops just below the upper edge of the neckband. The upper edge of the neckband is therefore a continuous selvage edge throughout its entire length.

Fig. 2 illustrates the neckband as it appears before being attached to the shirt. Fig. 3 shows the back portion of the neckband with the upper layer of the pocket cut down the center and folded back. The interwoven portions of the neckband are indicated by the numeral 4, the inside or lower flange or extension by the numeral 5 and the outside or upper flange or extension by 6. The piece of fabric 7 which is inserted in the pocket 1 and which forms the central flange, is secured at the upper and side edges of the pocket by the stitches 8. The said piece of fabric 7, in addition to providing the central flange, also strengthens and reinforces the neckband at the back buttonhole portion where a large proportion of the wear and strain on the neckband comes.

Fig. 4, which is a section taken on the line 4—4 of Fig. 3, illustrates conventionally the two ply interwoven fabric 4 of which the neckband is made. It will be noted that the flanges 5 and 6 on the lower edge of the neckband are extensions of the two plies of the neckband fabric, the interweaving having been omitted along the flange portion. Fig. 5 is a section taken through the back buttonhole portion along the line 5—5 of Fig. 2. The side faces of the pocket are unconnected and the lower edges thereof form the flanges 5 and 6. The additional layer 7 is inserted between the side faces of the pocket as illustrated. Fig. 6 is also a sectional view of the pocket taken along the line 6—6 of Fig. 2. The layer 7 is shown after being inserted in the pocket and secured by stitches 8.

Figs. 7 and 8 illustrate one method by

which the neckband may advantageously be attached to the shirt. The neckband, of which only the back portion is illustrated, is laid out flat with the buttonhole 3 on the upper side. The flange 6 is turned back and the shirt fabric is placed over the lower flange 5. The central flange 7 is then placed over the shirt fabric at the back buttonhole portion and a row of stitches 10 is put in to secure together the shirt fabric, the central flange and the lower flange. This is illustrated in Fig. 7. The upper flange 6 is then released and allowed to cover the exposed edge of the shirt fabric 9 and also the central flange 7. Stitches 11 are then put in as shown in Fig. 8. It will be noted that the flange 6 is sewed to the shirt fabric and lower flange at all points except the back buttonhole portion, where the stitches are omitted to leave an opening for the collar button. Furthermore it will be seen that at the back buttonhole portion the central flange 7 performs the same function that is performed by the flange 6 at the portions on both sides of the said back buttonhole portion. That is, the flange 7 covers the raw upper edge of the shirt fabric and, in conjunction with the stitches 10, secures the neckband thereto.

If it is found more convenient or desirable to do so, the piece of fabric 7 may be attached to the pocket at the same time and with the same operation that the shirt fabric is attached to the neckband. According to this method I place the neckband out flat with the buttonhole 3 in the upper side and turn back the flange 6. I then place the shirt fabric along the lower flange 5, and at the buttonhole portion I place the piece of fabric 7 (which is unattached to the neckband) over the shirt fabric so that its lower edge covers the upper edge of the shirt fabric and so that the remaining portion of the said piece 7 projects into the pocket 3. I then stitch together the lower flange 5, the central piece 7 and the shirt fabric 10. The last step in the attachment consists in placing the flange 6 over the exposed edge of the shirt fabric and also over the central flange 7, and passing a row of stitches along the flange 6 up to the back buttonhole portion around the side and upper edges of the pocket 3 (thus securing the piece 7 to the pocket) and continuing along the flange 6 on the other side of the said pocket. It will be noted that this method of attachment obviates the necessity of a separate and extra operation to attach the central flange 7 and the pocket 3.

The terms and expressions which I have employed are used as terms of description and not of limitation, and I have no intention, in the use of such terms and expressions, of excluding any equivalents of the features shown and described, or portions

thereof, but recognize that various modifications are possible within the scope of the invention claimed.

What I claim is:

the upper edge of the shirt fabric at the back buttonhole portion; securing together by a row of stitches the shirt fabric, the inner flange of the divided edge and the additional piece of fabric; placing the outer flange of the divided edge so that it overlies the upper edge of the shirt fabric and the additional piece of fabric; and passing a second row of stitches along the outer flange of the divided edge up to the back buttonhole portion, around the side and upper edges of the pocket, thus securing the additional piece of fabric to the pocket, and continuing along the outer flange of the divided edge on the other side of the said pocket, and leaving the outer flange unattached at the pocket.

6. That improvement in the art of making and attaching neckbands to shirts which consists in making a "multiple ply interwoven fabric" neckband having an inner and outer flange at the bottom forming a divided edge and having also, at the back buttonhole portion, a pocket formed by the separate layers of the said fabric neck-

band strip; positioning the neckband on the shirt so that the upper edge of the shirt fabric overlies the inner flange of the said divided edge; inserting an additional piece of fabric between the two layers of the pocket so that its lower edge overlies the upper edge of the shirt fabric at the back buttonhole portion; securing together by a row of stitches the shirt fabric, the inner flange of the divided edge and the additional piece of fabric; placing the outer flange of the divided edge so that it overlies the upper edge of the shirt fabric and the additional piece of fabric; and passing a second row of stitches along the outer flange of the divided edge up to the back buttonhole portion, around the side and upper edges of the pocket, thus securing the additional piece of fabric to the pocket, and continuing along the outer flange of the divided edge on the other side of the said pocket, and leaving the outer flange unattached at the pocket.

JOHN M. VAN HEUSEN.
